Primary Examiner — Mark A Goodwin(74) *Attorney, Agent, or Firm* — BakerHostetler(57) **CLAIM**

We claim the ornamental design for a mobile drive unit, as shown and described.

DESCRIPTION

FIG. 1 is a top perspective view of a mobile drive unit according to our new design;

FIG. 2 is a top plan view thereof;

FIG. 3 is a bottom plan view thereof;

FIG. 4 is a first side view thereof;

FIG. 5 is a second side view thereof;

FIG. 6 is a rear end view thereof; and,

FIG. 7 is a front end view thereof.

The broken, dashed lines illustrate environment structure and are not part of the claimed design sought to be patented. The dot-dash-dot lines show the boundaries of the claimed design.
